Attorney

UNITED STATES PATENT OFFICE.

FRED JOHN PFIFFER, OF LOS ANGELES, CALIFORNIA.

WINDOW-OPERATING MECHANISM.

Application filed June 21, 1926. Serial No. 117,442.

My invention relates to windows of the sliding sash type, and particularly to operating mechanisms therefor.

It is a purpose of my invention to provide a mechanism by which the sliding sashes of windows can be manually operated to occupy completely closed or open position and in intermediate position, the mechanism being characterized by instrumentalities which function automatically to lock either sash in closed or open position.

I will describe only one form of window operating mechanism embodying my invention and will then point out the novel features thereof in claims.

In the accompanying drawings,

Figure 1 is a view showing in side elevation and partly in section one form of window operating mechanism embodying my invention;

Figure 2 is a central vertical sectional view taken at right angles to Figure 1;

Figure 3 is a horizontal sectional view taken on the line 3—3 of Figure 2;

Figure 4 is a view similar to Figure 1 showing one extreme position of the mechanism.

Referring specifically to the drawings, in which similar reference characters refer to similar parts in each of the views, my invention, in its present embodiment, comprises a pair of rack bars R and R', one vertical edge of which is offset, as indicated at 15, and provided with openings through which the screws 16 extend for securing the bars to one and the same vertical edge of a pair of sliding window sashes S and S'. These rack bars R and R' are in the form of strips of metal provided at regular intervals along the length thereof with openings in which the teeth of gears are adapted to engage. As clearly illustrated in Figure 3, the rack bars by virtue of the offset edges 15 are spaced from the vertical edges of the window sashes, the free vertical edges of the bars being engaged, respectively, by strips of metal 17 and 17^a bent upon themselves and secured in the window frame by means of screws 18 to form limiting runners for the rack bars to maintain the latter in operative engagement with operating gears and yet allow of a limited

edgewise or horizontal movement of the window sashes so that the latter will have sufficient play to insure of proper movement thereof vertically within the window frame.

Within one side of the window frame is secured a frame having a back portion 19 and side portions 20 in which latter is mounted an axle 21 with gears 22 and 23 freely rotatable thereon and in slots 24 of the back 19, so as to have operative engagement with the rack bars R and R', respectively. These gears 22 and 23 constantly mesh with pinions 25 and 26, respectively, the latter being freely rotatable on a shaft 27 journaled in the sides 20 of the frame. The pinions are provided with slotted hubs 25^a and 26^a, respectively, the slots of which are adapted to receive pins 28 and 29, so as to key the pinions to the shaft, and thereby permit actuation of the pinion when the shaft is rotated. The shaft 27 is capable of longitudinal movement in the frame, and its outer end is provided with a crank 30 which projects from the inner side of the window frame for manual actuation to rotate the shaft in either direction and to move the shaft longitudinally in either direction.

On the shaft 27 between the pinions 25 and 26 is a sleeve 31 which operates to maintain the pinions in definite spaced relation. Freedly movable on the sleeve 31 is a wheel 32 keyed to the shaft 27 by a pin 33, the pin extending through slots 34 of the sleeve in order that the wheel can be moved longitudinally with the shaft. Coiled springs 35 and 36 are arranged on the sleeve between the wheel and the pinions so as to yieldably urge the wheel to the intermediate or neutral position shown in Figure 1.

The wheel 32 under the longitudinal movement of the shaft 27 is designed to move a pair of pawls 37 and 38 to released position with respect to the pinions 25 and 26, respectively. These pawls are pivoted on the axle 21 and yieldably urged into locking engagement with the pinions by means of springs 39 trained about the axle and having engagement with a lip 40 on the upper end of the frame. Arms 41 and 42 extend laterally from the confronting sides of the pawls 37

and 38 with their free ends bent downwardly to provide cams adapted to be engaged by the wheel 32 for moving the pawls to released position.

5 The operation of the mechanism is as follows: With the parts in the normal position as shown in Figure 1, both pawls 37 and 38 engage the pinions 25 and 26 to prevent rotation thereof by the shaft 27 or by the gears 10 22 and 23 should an attempt be made to move either sash S or S' so that the two sashes are locked against movement. The shaft 27 occupies what may be termed an intermediate position in which the hubs 25^a and 26^a are 15 out of engagement with the pins 28 and 29 so that rotation of the shaft will be ineffective to rotate the pinions. If it is desired to raise or lower the sash S' for example, the shaft 27 through the medium of the crank 30 20 is pulled outwardly to the extreme position shown in Figure 4, wherein the pin 28 engages the hub 25^a so as to provide an operative connection between the pinion 25 and the shaft. In moving the shaft to this extreme 25 position, a corresponding movement of the wheel 32 is effected so that the spring 35 is expanded and the spring 36 compressed, as shown in Figure 4. During this lateral movement of the wheel, it engages the cam end of 30 the arm 41, thereby elevating the pawl 37 out of engagement with the pinion 25 so that upon rotation of the shaft 27 the pinion will be actuated to rotate the gear 22 and through the medium of the corresponding rack R' 35 lower or elevate the sash S' according as the shaft 27 is rotated in one direction or the other. As this lateral movement of the wheel 32 is ineffective to actuate the arm 42, the pawl 38 remains in locking engagement with the pinion 26, and thus retains the other sash 40 S in locked position.

From the foregoing operation, it will be understood that to raise or lower the sash S it is only necessary to move the shaft 27 45 longitudinally to its other extreme position in which the pinion 26 through the medium of the slotted hub 26^a and the key 29 function to operatively connect the pinion to the shaft, the wheel 32 being shifted laterally in the other direction and engaging the cam end of the arm 42 to elevate the pawl 38 and thus release the pinion 26 so that upon rotation of the shaft 27 the gear 23 is actuated to raise or lower the sash S according as the shaft is 50 rotated in one direction or the other. During this operation, the pawl 37 remains in locked position with respect to the pinion 25 so that the sash S' is as a consequence retained in locked position.

55 Although I have herein shown and described only one form of window operating mechanism embodying my invention, it is to be understood that various changes and modifications may be made therein without departing from the spirit of the invention.

and the spirit and scope of the appended claims.

I claim as my invention:

1. A window operating mechanism comprising two gear and rack means for elevating and lowering the two sliding sashes of a window, manually operable means common to both of said means for actuating either means independently of the other, and locking means for each of the gear and rack means normally acting to lock both of said means and singly releasable by the manually operable means to permit actuation of the respective gear and rack means. 70

2. A window operating mechanism comprising two gear and rack means for elevating and lowering the two sliding sashes of a window, and a shaft movable to either of two extreme positions in which it can be manually rotated to actuate one gear and rack means or the other according as it occupies one extreme position or the other, and means for yieldably urging the shaft to an intermediate position in which neither gear and rack means can be operated. 80 90

3. A window operating mechanism comprising two gear and rack means for elevating and lowering the two sliding sections of the window, a shaft mounted to rotate and movable longitudinally to either of two extreme positions, and an intermediate position, and two pinions on the shaft having operative connection with the gear and rack means for actuating the latter when rotating, said pinions freely rotatable on the shaft when the latter is in intermediate position, and means by which one pinion or the other is keyed to the shaft for rotation thereby, according as the shaft occupies one extreme position or the other, whereby one gear and rack means or the other can be actuated. 95 105

4. A window operating mechanism comprising two gear and rack means for elevating and lowering the two sliding sections of the window, a shaft mounted to rotate and movable longitudinally to either of two extreme positions and an intermediate position, and two pinions on the shaft having operative connection with the gear and rack means for actuating the latter when rotating, said pinions freely rotatable on the shaft when the latter is in intermediate position, means for keying one pinion or the other to the shaft according as the shaft is moved to one extreme position or the other so that when rotated it will actuate one pinion or the other, and means for yieldably urging the shaft to the intermediate position. 110 120 115

5. A window operating mechanism comprising two gear and rack means for elevating and lowering the two sliding sections of the window, a shaft mounted to rotate and movable longitudinally to either of two extreme positions and an intermediate position, two pinions on the shaft having operative connec- 125 130

tion with the gear and rack means for actuating the latter when rotating, said pinions freely rotatable on the shaft when the latter is in intermediate position, means for keying one pinion or the other to the shaft according as the shaft is moved to one extreme position or the other so that when rotated it will actuate one pinion or the other, means for yieldably urging the shaft to the intermediate position, a pair of pawls one for each of the pinions for locking the latter against actuation and yieldably urged to locking position, and a wheel urged to a neutral position with respect to the pawls and operable upon longitudinal movement of the shaft to move one pawl or the other to released position according as the shaft occupies one extreme position or the other.

6. A window operating mechanism comprising two gear and rack means for elevating and lowering the two sliding sections of the window, a shaft mounted to rotate and movable longitudinally to either of two extreme positions and an intermediate position, two pinions on the shaft having operative connection with the gear and rack means for actuating the latter when rotating, said pinions freely rotatable on the shaft when the latter is in intermediate position, means for keying one pinion or the other to the shaft according as the shaft is moved to one extreme position or the other so that when rotated it will actuate one pinion or the other, means for yieldably urging the shaft to the intermediate position, a pair of pawls one for each of the pinions for locking the latter against actuation and yieldably urged to locking position, arms on the pawls having cams, and a wheel movable longitudinally with the shaft to engage one cam or the other according as the shaft is moved to one extreme position or the other and to, therefore, move one pawl or the other to released position with respect to the corresponding pinion.

7. A window operating mechanism comprising gear and rack means including rack bars adapted to be secured to the edges of sliding window sashes and gears engaging the rack bars, and means for maintaining the rack bars in operative engagement with the gears irrespective of the horizontal movement of the window sashes.

8. A window operating mechanism as embodied in claim 7 wherein said means comprises strips adapted to be secured to the window frame and engaging the rack bars.

9. A window operating mechanism comprising two gear and rack means for elevating and lowering the two sliding sashes of a window, and manually operable means common to both of said means for actuating the latter and including clutch means by which either of said two means can be op-

eratively connected to said actuating means independently of the other.

10. A window operating mechanism comprising two gear and rack means for elevating and lowering the two sliding sashes of a window, manually operable means common to both of said means for actuating the latter and including two clutch means one for each of the means, and normally disconnected from said two means, and operable simultaneously by said actuating means to operatively connect the latter to either of said two means independently of the other.

11. A window operating mechanism comprising two gear and rack means for elevating and lowering the two sliding sections of a window, a shaft mounted to rotate and movable longitudinally to any one of three positions, two means rotatable on the shaft when in one of its positions, and having operative connection with the first means for actuating the latter, and means by which one or the other of said two rotatable means is operatively connected to the shaft for rotation thereby according as the shaft occupies one or the other of its other two positions, whereby one or the other of first said two means can be actuated.

12. A window operating mechanism as embodied in claim 11 wherein means is provided for yieldingly urging the shaft to the first one of its positions.

13. A window operating mechanism comprising two means for elevating and lowering the two sliding sections of a window, a shaft mounted to rotate and movable longitudinally to any one of three positions, two means rotatable on the shaft when in one of its positions, and having operative connection with the first means for actuating the latter, means by which one or the other of said two rotatable means is operatively connected to the shaft for rotation thereby according as the shaft occupies one or the other of its other two positions, whereby one or the other of first said two means can be actuated, two means, one for each of said two rotatable means for locking the latter against rotation and normally occupying a locking position, and means operable upon longitudinal movement of the shaft to move one or the other of said locking means to a released position according as the shaft occupies one or the other of its other two positions.

14. A window operating mechanism comprising two means for elevating and lowering the two sliding sections of a window, a shaft mounted to rotate and movable longitudinally to any one of three positions, two means rotatable on the shaft when in one of its positions, and having operative connection with the first means for actuating the latter, means by which one or the other of said two rotatable means is operatively connected to the shaft

for rotation thereby according as the shaft occupies one or the other of its other two positions, whereby one or the other of first said two means can be actuated, two means, one for each of said two rotatable means for locking the latter against rotation and normally occupying a locking position, cam means on each of said locking means, and means mov-

able longitudinally with the shaft to engage one cam means or the other according as the shaft is moved to one or the other of its other two positions and to thereby move one locking means or the other to released position with respect to the corresponding one of the two rotatable means.

FRED JOHN PFIFFER.
